FACE GUARD FOR A FOOTBALL HELMET

Vernon R. McMillan, 726 Wabash Ave.,
Terre Haute, Ind.

Filed Feb. 19, 1960, Ser. No. 59,447

Term of patent 14 years

(Cl. D3—13)

FIGURE 1 is a front perspective view of a face guard for a football helmet, showing my new design, the broken line showing of the helmet being for illustrative purposes only.

I claim:

The ornamental design for a face guard for a football helmet, substantially as shown and described.
